ATION OF OHIO.

LIFTING-JACK FOR TRUCKS.

1,388,836.

Specification of Letters Patent. Patented Aug. 23, 1921.

Application filed February 2, 1920. Serial No. 355,719.

To all whom it may concern:

Be it known that we, CHARLES W. RIPSCH, JAMES C. DAWLEY, and CHARLES D. DERBY, citizens of the United States, residing at 5 Dayton, in the county of Montgomery and State of Ohio, have invented certain new and useful Improvements in Lifting-Jacks for Trucks, of which the following is a specification, reference being had therein to the 10 accompanying drawing.

This invention relates to lifting jacks and more particularly to a jack designed for use with trucks, or similar vehicles.

The object of the invention is to provide 15 a simple, efficient jack which may be easily operated under all conditions of service.

A further object is to provide a jack of this kind with means controlled by the operating lever for reversing the direction of 20 movement of the lifting element, thus enabling the jack to be reversed without the necessity of the operator reaching or crawling under the load to operate the reversing device.

25 It is also an object of the invention to provide a jack of this kind with a load engaging part which is movably connected with the lifting element so that the lifting element when in its lowermost position can be brought into operative relation to loads at 30 different heights, thus enabling the jack to be applied to either the front or rear axle of a truck when these axles are of different heights, as when the front wheels are 35 equipped with solid tires and the rear wheels with pneumatic tires.

Other objects of the invention will appear as the mechanism is described in detail.

In the accompanying drawings Figure 1 40 is a top plan view of a jack embodying my invention; Fig. 2 is a side elevation of the same, partly broken away; Fig. 3 is a front elevation of the same; Fig. 4 is a transverse sectional view taken on the line 4—4 of Fig. 45 2 showing the pawl controlling means in a neutral position; Fig. 5 is a perspective view, partly broken away, of the operating mechanism, showing the lowering pawl in its inoperative position; and Fig. 6 is a section on the line 6—6 of Fig. 2.

In carrying out the invention we provide a jack in which the lifting element is operated by a ratchet wheel with which co- 50 operates a pawl, or pawls, which may be adjusted to move the lifting element in either

direction. The operating lever is so arranged that it may be rotated about a longitudinal axis and that this rotation will so adjust the pawl, or pawls, as to reverse the direction of movement of the jack. The lever, when in its operative position, is locked to the jack structure and may be used as a handle to facilitate the positioning of the jack. The lifting element is provided with a load engaging part which is movable relatively thereto to enable the lifting element to be brought into operative relation with the load at different heights, while the lifting element is in its lowermost position, and to thereby enable the jack to engage 60 loads at different distances from the ground without decreasing the scope of the lifting action of the jack. The invention may be embodied in structures of various kinds and it will be understood that the particular jack 65 here illustrated has been chosen for the purposes of illustration only.

In the particular form of the invention here illustrated the jack comprises a base 1 having an upwardly extending hollow standard 2, the upper portion of which is provided with internal threads 3 to constitute a nut. The lifting element is in the form of a screw 4 threaded into the nut 3 and this screw is preferably hollow and provided 70 at its upper end with threads 5 to constitute a nut to receive a second screw 6, and this second screw is provided at its upper end with a load engaging part, or cap, 7. To operate the jack rotatory movement is imparted 75 to the outer screw 4 and inasmuch as the threads of the two screws are arranged in different directions it will be apparent that the rotation of this outer screw will not only move the same vertically relatively to the standard 2 but will also cause the inner screw to move vertically relatively to the outer screw. Rotation may be imparted to the outer screw 4 in any suitable manner but preferably pawl and ratchet mechanism is 80 employed for this purpose. In the present instance a ratchet wheel 8 is rigidly secured to the screw 4 and is arranged in a substantially horizontal position. A pawl, or pawls, coöperate with this ratchet wheel to 85 rotate the same and the pawls are in turn operated by a suitably operating member. In the present construction we have embodied two pawls, 9 and 10, and these pawls are mounted in laterally extending guide 90 95 100 105 110

ways or housings, 11 projecting in opposite directions from a lever socket 12. This lever socket, or pawl supporting structure, is mounted for rotation about the axis of the screw 4 and is preferably provided with collars 13 which extend about the screw above and below the ratchet wheel 8 and are free to rotate thereon, it being noted that the upper end portion of the screw 4 is without threads. The pawls may be of any suitable character but in the construction here shown they are cylindrical in shape and have their sides adjacent to the ratchet wheel beveled to engage the teeth of the ratchet wheel. As here shown, the teeth of the ratchet wheel and the pawls are V-shaped so that each pawl will operate upon the ratchet wheel with equal facility. The pawls are held normally in their innermost, or operative, positions by means of springs 14 confined between the outer ends thereof and end plates 15 mounted in the ends of the guide-ways, or housings, 11. Because of the curved shape of the pawls and their guide-ways, the pawls are capable of movement about their longitudinal axes and will therefore automatically align themselves with the teeth of the ratchet wheel and thus cause the teeth of the pawl to have a full bearing upon the teeth of the ratchet wheel. The pawls are held in proper positions to engage the ratchet wheel by means of pins 16 which extend through guide slots 117 in the walls of the housings 11, but these slots are of sufficiently greater width than the diameter of the pins to permit of sufficient rotatory movement of the pawls to enable them to align themselves with the teeth of the ratchet wheel. Preferably the outer end of each pin projects beyond the outer wall of the housing and forms a finger piece by means of which the pawl may be manually retracted.

The lever socket 12 is adapted to receive an operating lever, or bar, 17 which is removably mounted therein, and it will be noted that the lever and the pawl and ratchet mechanism are so arranged that the lever will be moved in substantially a horizontal plane, thus enabling the jack to be operated under conditions of the load or ground which would render difficult the manipulation of a vertically movable lever. In order to permit the pawls to be reversed when it is desired to lower the load without the necessity of the operator reaching or crawling under the load to operate the reversing mechanism we have provided means whereby this reversal may be accomplished from a point more or less remote from the jack itself. To accomplish this the lever 17 is rotatable in the socket 12 and is adapted for connection with either pawl to move that pawl into its inoperative position. In the present construction the lever is provided on its inner end with an eccentric pin, or stud, 18 which lies between the inner ends of the two pawls and may be brought into operative engagement with either of them by the rotation of the lever about its horizontal axis. The outer portion of the lever socket 12 is provided with an internal groove 19 and a slot 20 leading from the outer end of the socket to the groove and preferably arranged approximately midway between the ends of the groove. A pin 21 is mounted in the lever and arranged to enter the groove 19 through the slot 20. The position of the pin 21 with relation to the eccentric stud 18 is such that the pin can only enter the slot 20 when the stud is in its central, or neutral, position, that is, when it is in line with the space between the ends of the two pawls. When the lever has been so inserted in the socket and is rotated in one direction or the other, to render one pawl or the other inoperative, the pin 21 will be moved out of alignment with the slot 20 and the lever will be locked in the socket. The ends of the internal groove 19 are so arranged that they will check the movement of the lever when the stud 18 is in a position to render inoperative that pawl with which it is in engagement. The lever 17 may be provided with markings of some sort to indicate the positions of the pawls. As here shown, the lever has its outer end curved to constitute a pinch bar, as shown at 32, and the eccentric stud 18 is so arranged with relation to this curved end of the lever, that when the stud 18 is in a position to render the lowering pawl inoperative the curved end of the lever will extend upwardly and when the stud is in a position to render the lifting pawl inoperative the curved end of the lever will extend downwardly. By locking the lever in its socket 12 we are enabled to utilize the lever to shift the position of the jack when the latter is being placed in position and to thus greatly facilitate this operation.

It not infrequently happens, particularly in connection with trucks and the like, that the parts which are to be engaged by the jack are at different distances from the ground, and a jack which is low enough to go under the lower part must be extended more or less in order to engage the higher part, consequently the distance which the higher part can be moved by the jack is correspondingly restricted. This is especially true in trucks in which the front wheels are equipped with solid tires and the rear wheels with pneumatic tires of large diameter. In order to provide a single jack which will operate under either axle and will impart the same amount of movement to either axle, we have provided the lifting element of the present jack with a movable load engaging member which may be moved

110

115

120

130

into such a position with relation to the lifting element as to enable that element while in its lowermost position to be brought into operative relation with the higher axle, or 5 other parts which is to be engaged. Preferably this movable load engaging part is of a supplemental character and is provided in addition to the usual load engaging part 7. As here shown, the movable load engaging 10 part is in the form of a block, or head, 22 which is movably connected with the inner screw 6 in such a manner that it may be moved into and out of alignment therewith. Preferably the second, or supplemental, 15 load engaging part is pivotally connected to the first, or main, load engaging part 7 and as here shown it is provided with pivot lugs 23 which embrace a lug 24 extending laterally from the load engaging part, or cap, 7 and are secured thereto by a pivot pin 25. Coöoperating lugs 26 and 27 serve to limit the downward movement of the movable load engaging part. When the load engaging part 22 is in its operative, or upright, 20 position it rests upon the load engaging part 7 and constitutes an extension thereof. The load engaging part, or cap, 7 is provided with an annular flange 28 which forms a seat to receive the reduced lower end portion 25 of the part 22 and to hold the part 22 against lateral strains. To hold the part 22 against any tendency to turn about a longitudinal axis relatively to the part 7, the latter is provided with a transverse 30 groove 30 into which projects a rib 31 rigidly secured to and preferably formed integral with the lower end of the movable part 22. It will be apparent that when the jack is to be applied to a low part, such as 35 a front axle, the movable load engaging part is swung to one side and will then occupy a position in which it will in no way interfere with the operation of the jack. When the jack is to be applied to a higher part, 40 such as a rear axle, the movable part 22 is moved into its upright position, in which it rests upon the lower part 7, and this movable part is then brought into operative relation with the part to be lifted. The cap 7 is 45 attached to the inner screw 6 by extending the reduced upper end of that screw through an opening in the cap, which opening is countersunk at its upper end to permit the end of the screw to be upset or riveted to 50 the cap. To hold the cap firmly against rotation on the screw we have provided the countersunk opening therein with a plurality of grooves or notches 33 into which projections from the end of the screw will 55 be forced by the upsetting or expanding thereof, thus forming a rigid nonrotatable connection between the two parts.

While we have shown and described one embodiment of our invention we wish it to 60 be understood that we do not desire to be

limited to the details thereof as various modifications may occur to a person skilled in the art.

Having now fully described our invention, what we claim as new and desire to 70 secure by Letters Patent, is:

1. In a lifting jack, the combination with a base, a lifting element movably mounted on said base, and a ratchet wheel operatively connected with said lifting element, of a 75 pawl to coöperate with said ratchet wheel, a lever operatively connected with said pawl, and a part rigidly secured to said lever and arranged to move said pawl into an inoperative position when said lever is moved 80 about its longitudinal axis.

2. In a lifting jack, the combination with a base, a lifting element movably mounted on said base, and a ratchet wheel operatively connected with said lifting element, of a 85 pair of independently movable pawls to coöperate with said ratchet wheel to respectively move the same in opposite directions, a lever to actuate said pawls, and means controlled by rotation of said lever to move 90 one of said pawls into an inoperative position.

3. In a lifting jack, the combination with a base, a lifting element movably mounted on said base, and a ratchet wheel operatively 95 connected with said lifting element, of a pair of pawls to coöperate with said ratchet wheel to respectively move the same in opposite directions, a lever to actuate said pawls and mounted for rotation about a longitudinal 100 axis, and means carried by said lever to engage one of said pawls and move the same into an inoperative position when said lever is moved about said longitudinal axis.

4. In a lifting jack, the combination with 105 a base, a lifting element movably mounted on said base, and a ratchet wheel operatively connected with said lifting element, of a pair of pawls to coöperate with said ratchet wheel to respectively move the same in opposite 110 directions, a lever to actuate said pawls and mounted for rotation about a longitudinal axis, a part rigidly secured to said lever to engage one of said pawls and move the same 115 into an inoperative position when said lever is moved about its longitudinal axis.

5. In a lifting jack, the combination with a base, a lifting element movably mounted on said base, and a ratchet wheel operatively connected with said lifting element, of a 120 pair of pawls to coöperate with said ratchet wheel, springs tending to move said pawls one toward the other to cause them to operatively engage said ratchet wheel, a lever to operate said pawls, said lever being capable of rotation about a longitudinal axis, and a part actuated by said lever to engage one of said pawls and move it out of engagement with said ratchet wheel.

6. In a lifting jack, the combination with 125

4
a base, a lifting element movably mounted on said base, and a ratchet wheel operatively connected with said lifting element, of a pair of opposed pawls having their inner ends spaced apart, springs to move said pawls one toward the other to cause them respectively to engage said ratchet wheel, a lever to operate said pawls, said lever being capable of rotation about a longitudinal axis, and a part carried by said lever and extending between the inner ends of said pawls and arranged to engage one of said pawls to move the same into an inoperative position when the lever is rotated about a longitudinal axis.

7. In a lifting jack, the combination with a base, a lifting element movably mounted on said base, and a ratchet wheel operatively connected with said lifting element, of a lever socket mounted for rotation about the axis of said ratchet wheel, a pawl mounted on said lever socket and held normally in engagement with said ratchet wheel, a lever mounted within said socket for rotation relatively thereto, and a part actuated by the rotation of said lever to move said pawl into an inoperative position.

8. In a lifting jack, the combination with a base, a lifting element movably mounted on said base, and a ratchet wheel operatively connected with said lifting element, of a structure mounted for rotation about the axis of said ratchet wheel and comprising a lever socket, and guideways extending laterally from said lever socket, pawls mounted in said guideways and held normally in engagement with said ratchet wheel, and means actuated by the rotation of said lever to move one of said pawls into its inoperative position.

9. In a lifting jack, the combination with a base, a lifting element movably mounted on said base, and a ratchet wheel operatively connected with said lifting element, of a structure mounted for rotation about the axis of said ratchet wheel and comprising a lever socket and guideways extending laterally in opposite directions from said socket, pawls slidably mounted in said guideways, springs for moving said pawls one toward the other to cause them to respectively engage said ratchet wheel, a lever rotatably mounted in said socket, and a stud eccentrically mounted on the end of said lever and projecting between the adjacent ends of said pawls to move one or the other of said pawls into an inoperative position when said lever is rotated in said socket.

10. In a lifting jack, the combination with a base, a lifting element movably mounted on said base, a ratchet wheel operatively connected with said lifting element, and a lever socket movable about the axis of said ratchet wheel, of a pair of pawls slidably mounted on said socket to respectively move

said ratchet wheel in opposite directions, a lever rotatably mounted in said socket, and means actuated by the rotation of said lever to move one of said pawls out of engagement with said ratchet wheel.

11. In a lifting jack, the combination with a base, a lifting element mounted on said base, and pawl and ratchet mechanism to move said lifting element in either direction, of an operating lever for said pawl and ratchet mechanism capable of rotatory movement, and a part carried by said lever and arranged to reverse said pawl and ratchet mechanism when rotatory movement is imparted to said lever.

12. In a lifting jack, the combination with a base, a lifting element movably mounted on said base and a ratchet wheel operatively connected with said lifting element, of a lever socket mounted for movement about the axis of said ratchet wheel, guideways carried by said lever socket, pawls slidably mounted in the respective guideways to co-operate with said ratchet wheel, said pawls being capable of movement about their longitudinal axes to aline the same with the teeth of said ratchet wheel, a lever mounted in said socket and capable of rotatory movement therein, and a part actuated by the rotation of said lever to control the positions of said pawls.

13. In a lifting jack, the combination with a base, a lifting element movably mounted on said base, and a ratchet wheel operatively connected with said lifting element, of a lever socket mounted for movement about the axis of said ratchet wheel, cylindrical guideways extending laterally from the opposite sides of said socket, pawls in said cylindrical guideways having teeth to engage said ratchet wheel, a lever rotatably mounted in said socket, and means actuated by the rotation of said lever for controlling the positions of said pawls.

14. In a lifting jack, the combination with a base, a lifting element movably mounted on said base, and a ratchet wheel operatively connected with said lifting element, of a lever socket mounted for rotation about the axis of said ratchet wheel, cylindrical guideways extending laterally from the opposite sides of said socket and each having a longitudinal slot therein, pawls mounted in the respective guideways and having teeth to co-operate with the teeth of said ratchet wheel, pins carried by said pawls and projecting through the respective slots, said pins having a diameter less than the width of said slots, springs acting on the respective pawls to move the same into engagement with said ratchet wheel, and means for retaining a selected pawl in an inoperative position.

15. In a lifting jack, the combination with a base, a lifting element movably mounted

70

80

90

105

115

120

125

130

- on said base, and a ratchet wheel operatively connected with said lifting element, of a lever socket mounted for rotation about the axis of said ratchet wheel, cylindrical guideways extending laterally from the opposite sides of said socket and each having a longitudinal slot therein, pawls mounted in the respective guideways and having teeth to coöperate with the teeth of said ratchet wheel, pins carried by said pawls and projecting through the respective slots, said pins having a diameter less than the width of said slots, springs acting on the respective pawls to move the same into engagement with said ratchet wheel, a lever mounted in said socket for rotatory movement, and a part carried by said lever to move either of said pawls into an inoperative position.
16. In a lifting jack, the combination with a base, a lifting element movably mounted on said base, and a ratchet wheel operatively connected with said lifting element, of a lever socket mounted for rotation about said ratchet wheel in a substantially horizontal plane, guideways carried by said socket, pawls slidably mounted in the respective guideways and adapted to coöperate with said ratchet wheel to move the same in opposite directions, a lever mounted for rotatory movement in said lever socket, and means actuated by said lever to render a selected one of said pawls inoperative.
17. In a lifting jack, the combination with a base, a lifting element movably mounted on said base, and a ratchet wheel operatively connected with said lifting element, of a lever socket mounted for rotation about said ratchet wheel, a pawl carried by said lever socket, a lever mounted in said socket, and means for removably locking said lever in said socket.
18. In a lifting jack, the combination with a base, a lifting element movably mounted on said base, and a ratchet wheel operatively connected with said lifting element, of a lever socket mounted for rotation about the axis of the ratchet wheel, a pair of pawls carried by said socket to coöperate with said ratchet wheel, springs tending to move said pawls into engagement with said ratchet wheel, a lever adapted to enter said socket, said socket having an internal groove and a slot leading to said groove, a pin carried by said lever and adapted to enter said groove when said lever is placed in position in said socket, and a part actuated by the rotation of said lever to control the positions of said pawls.
19. In a lifting jack, the combination with a base, a lifting element movably mounted on said base, and a ratchet wheel operatively connected with said lifting element, of a lever socket mounted for rotation about the axis of said ratchet wheel, springs to move said pawls into engagement with said ratchet wheel, a lever mounted in said socket for rotatory movement relatively thereto, and a part carried by said lever and actuated by the rotatory movement thereof to move one of said pawls into an inoperative position, said socket and said lever having co-operating parts to limit the rotation of said lever.

In testimony whereof, we affix our signatures hereto.

CHARLES W. RIPSCH.
JAMES C. DAWLEY.
CHAS. D. DERBY.
